UNITED STATES PATENT OFFICE

DAVID FISHER, OF PADEN CITY, WEST VIRGINIA

DESIGN FOR A CUP

Application filed January 5, 1933. Serial No. 46,738. Term of patent 3½ years.

To all whom it may concern:

Be it known that I, DAVID FISHER, a citizen of the United States, and a resident of Paden City, in the county of Wetzel and State of West Virginia, have invented a new, original, and ornamental Design for a Cup, of which the following is a specification, reference being had to the accompanying drawing, forming a part hereof.

I claim:

The ornamental design for a cup, as shown.

DAVID FISHER.
